UNITED STATES PATENT OFFICE.

ADAM EGOLF, OF ROYER'S FORD, PENNSYLVANIA, ASSIGNOR OF ONE-HALF
TO SAMUEL EGOLF, OF SAME PLACE.

ALARM-BOLT.

SPECIFICATION forming part of Letters Patent No. 236,315, dated January 4, 1881.

Application filed October 26, 1880. (Model.)

To all whom it may concern:

Be it known that I, ADAM EGOLF, a citizen of the United States, residing in Royer's Ford, Montgomery county, Pennsylvania, have invented an Improved Alarm-Bolt, of which the following is a specification.

The main object of my invention is to provide the locking-bolt of a door or shutter with mechanism whereby, on an attempt being made to open the door or shutter, when the bolt is projected an alarm will be given, a further object being to secure the bolt in position after the sounding of the alarm, and thereby prevent the retraction of said bolt from the outside of the door or shutter.

In the accompanying drawings, Figure 1 is a vertical section of a locking-bolt with my improved alarm mechanism; Figs. 2 and 3, sectional plans of Fig. 1, and Figs. 4 and 5 detached perspective views of parts of the alarm mechanism.

A represents part of a window-shutter, and B part of the opposite shutter; or B may represent part of a door-frame, and A part of a door opening outwardly. For the purpose of this description, however, I will regard these parts as window-shutters. The shutter A carries on the inside a plate, D, with staples a for the retention and guidance of the bolt E, and the shutter B has a plate, F, with staples b for the reception and retention of the end of said bolt when the latter is projected. The bolt E has a slot, d, for the reception of a hammer, G, which is hung to a suitable pivot-pin, e, and is acted upon by a spring, f, as shown in Fig. 1. The lower portion of the slot d extends to the inner face of the bolt E, and in this portion of the slot is pivoted a trigger, i, which is acted upon by a spring, m, and is adapted to engage with a notch, n, in the hammer when the latter is elevated, as shown in Figs. 1 and 2. The rear end of the trigger projects from the inner face of the bolt, which is beveled to permit such projection, the heel of the bolt being reduced in thickness, as shown in Fig. 2. An opening, p, is formed in the bolt E for the reception of a cap or cartridge, s, the opening occupying such relation to the pivot of the hammer G

that when said hammer is depressed its point 50 will occupy the opening.

When the hammer is elevated and is retained in its elevated position by the engagement of the front end of the trigger i with the notch n, the bolt E can be moved backward 55 and forward to fasten or unfasten the shutter without danger of releasing the hammer, as no pressure is exerted upon the projecting end of the trigger; but when the bolt is projected and any attempt is made to open the shutter 60 without first retracting the bolt—such, for instance, as an attempt to pry open the shutters—the angle assumed by the latter causes pressure upon the projecting end of the trigger i and operates the latter so as to release the 65 hammer G, which descends and explodes the cap or cartridge s in the opening p. (See Fig. 3.) After its descent the point of the hammer rests in the opening p, and said hammer embraces the staple a, so that the retraction of the bolt 70 to release the shutters cannot be effected without first elevating the hammer.

The various forms of hammers and triggers can be adopted in carrying out my invention, those shown merely embodying my invention 75 in a simple form which has been found to be effective in practice.

When the bolt is applied to a pair of shutters or a door opening inwardly the shape of the bolt and the location of the trigger will 80 have to be modified accordingly.

I claim as my invention—

1. A locking-bolt constructed for the reception of a cap or cartridge, and carrying a hammer, G, and trigger i, and springs for operating the same, as set forth.

2. The combination of the hammer G and trigger i and their springs with a bolt constructed for the reception of a cap or cartridge, and having a slot, d, for receiving said hammer, trigger, and springs, as set forth.

3. The combination of a pair of shutters, or a door and door-frame, a plate, F, having staples b, a plate, D, having staples a, and a bolt, E, adapted to said staples a and b, provided with a hammer, G, and trigger i, and constructed for the reception of a cap or cartridge, as specified.

4. The combination of a pair of shutters, or a door and door-frame, a plate, F, having staples *b*, a plate, D, having staples *a*, and a slotted bolt, E, adapted to the staples *a* and *b*, 5 provided with a hammer, G, and trigger *i*, and having its inner face beveled or cut away to permit the projection of the trigger, as described.
5. The combination of the plate D, having 10 staples *a*, with the bolt E, having an opening, *p*, and a hammer hung in respect to the opening, as set forth, whereby, when the bolt is

projected and the hammer depressed, said hammer will embrace the outer staple, *a*, and confine the bolt longitudinally thereto, as set 15 forth.

In testimony whereof I have signed my name to this specification in the presence of two subscribing witnesses.

ADAM EGOLF.
